UNITED STATES PATENT OFFICE.

FRANK J. HINDERLITER, OF TULSA, OKLAHOMA.

BIT FORGE.

Application filed February 23, 1927, Serial No. 170,187. Renewed August 23, 1928.

In the forging of bits for use in connection with drilling oil wells and the like considerable trouble has been experienced due to the fact that a great many bits are 5 broken or rendered unfit for use, due to the fact that the flame enters a forge in such a way that it is permitted to circle over the cutting edge of a bit and heats the blade back of said cutting edge directly in the 10 water course. Moreover, the web of the said bit being thin is adapted to absorb the heat quicker than the heavy sections thereby causing the web to expand prior to the expansion of the heavy sections, thereby usually 15 causing the bit to burst or crack in lengths usually from three to six inches in a diagonal direction. The crack does not always run out to the cutting edge due to the temper of said edge so that the defect is not observed until after the bit has been in use and 20 breaks. As a result of the above procedure the bits are not evenly heated and are furthermore not properly treated or tempered after being heated which accounts for a 25 large proportion of the bits breaking when put into use.

This invention relates to an improved bit forge so constructed that a bit is adapted to be evenly heated by swirling blast flames 30 entering the fire chamber without coming into direct contact with the bit or steel being heated, thereby permitting the steel to be tempered at a rising heat after which the bit is permitted to lay on an anvil after dressing 35 until a hand can be laid on the same; the bit may now be placed back in the forge and given a short heat on the end of the bit until the bit is brought up to a dark cherry red color after which the bit is removed and 40 then put in a clean slack tub.

It is an object of this invention to provide a bit forge of simplified construction permitting a bit to be evenly heated at its drilling end without causing bursting of 45 the enlarged end of the bit which is permitted to be heated prior to the heating of the thin web formed between the water courses of the bit.

It is also an object of this invention to 50 provide a simplified forge with a refractory lining, different sections of which are of different thicknesses, to provide a main fire chamber, an entrance for a bit, and a rear or inner chamber or recess permitting the 55 enlarged or heavy end sections of the bit to

be heated prior to the heating of the web between the water courses thereby producing an even heating of the bit obviating bursting.

It is an important object of this invention 60 to provide an improved simplified forge having an outer casing containing a refractory lining constructed to afford a fire chamber and an auxiliary rear fire pocket permitting flames which enter the fire chamber tangentially to whirl around in the fire chamber and pocket to permit the enlarged end or heavy section of a bit to be heated prior to the heating of the web to obviate bursting of the bit and the elimination of 70 any cracks therein.

Other and further important objects of this invention will be apparent from the disclosures in the specification and the accompanying drawings.

This invention (in a preferred form) is 75 illustrated in the drawings and hereinafter more fully described.

On the drawings:

Figure 1 is a side elevation of an improved forge embodying the principles of this invention and showing a fragmentary portion of a bit projecting into the forge.

Figure 2 is an enlarged transverse section of the upper portion of the forge taken on 85 line II—II of Figure 1 with parts shown in elevation.

Figure 3 is a horizontal section taken on line III—III of Figure 2 with a fragmentary portion of a bit shown in elevation.

As shown on the drawings:

The reference numeral 1 indicates a supporting framework or stand supported by rollers or casters 2 to permit the forge to be readily moved about. Supported on the frame 1 is an outer sheet metal casing 3 of cylindrical form open at the front end and provided with a rear wall 4 having a central opening at 5. The opening 5 is closed by means of a metal ring plate 6 and a closure plate or disk 7 which is secured to the ring plate 6 to close the opening therein. The casing 3 is provided with a lining constructed of standard fire bricks made of fused silicon carbide, carborundum, or any 95 other suitable refractory material. The refractory bricks are arranged in a predetermined order to provide an outer lining or shell 8 consisting of three adjacently disposed rings or layers of bricks which form 100

105

110

an outer lining which extends from the front to the rear of the outer casing 3. Mounted within the outer lining 8 is a rear wall or rear lining comprising two concentric annular rows or layers of fire bricks 9 and 10 which contact against the inner face of the rear casing wall 4 and project forwardly to overlap the intermediate annular row or layer of fire bricks forming part of the outer fire brick lining 8. The inner periphery of the annular row of fire bricks 10 registers with the periphery of the opening 5 within the rear casing wall 4, thereby affording a rear pocket or recess 11 closed at one end by the overlapping metal plates 6 and 7 and having the other end thereof communicating with the middle portion of a fire or main chamber 12 formed by the middle annular row of fire bricks of the outer lining 8 and the rear lining wall 9—10, together with a front lining wall 13 constructed of standard refractory fire bricks of but a single row or layer positioned within the front portion of the outer lining 8 and extending rearwardly a distance sufficient to overlap a portion of the intermediate annular row of fire bricks forming part of the outer lining 8. The front lining wall 13 being of annular construction affords an entrance opening 14, the inner end of which communicates with the main fire chamber 12. The entrance opening 14 has a greater diameter than the diameter of the rear pocket 11 and is axially aligned therewith. The complete lining of the forge consisting of the annular rows or layers of fire brick 8, 9, 10, and 13 thus affords three communicating chambers with the main fire chamber 12 having the greatest diameter and being positioned between the pocket 11 and the entrance opening 14.

Fuel is supplied to the forge by means of a main fuel supply pipe 15 adapted to be connected with any suitable source of oil or gas fuel. The end of the main fuel pipe 15 terminates in a branch fuel supply pipe 16 which projects through a suitable opening in the outer casing 3 and the middle row of fire bricks forming the middle part of the outer lining 8. The lower auxiliary fuel supply pipe 16 has the mouth thereof terminating in the main fire chamber 12 in such a position that a blast of fuel flames is adapted to be directed tangentially into the lower portion of the main fuel chamber 12. The flames entering from the lower auxiliary fuel supply pipe 16 impinges against the circular wall of the chamber 12 which causes the flames to whirl around the outer peripheral portion of the chamber 12 to commingle with a similar flame tangentially entering the upper portion of the chamber 12 through the mouth of a second or upper auxiliary fuel supply pipe 17 which projects into the upper portion of

the forge and has the outer end 18 thereof curved or bent around the exterior of the forge casing 3, with the lower end of said exterior pipe 18 connected with the main fuel supply 15 at a point adjacent the lower auxiliary fuel supply pipe 16, as clearly illustrated in Figure 2. Mounted on the exterior of the front side of the forge supporting framework 1 is a bracket 19 supporting a table or shelf 20 having a rounded bead or guide flange 21 formed thereon to afford a guide and support for the drilling end of a bit or other tool which is to be tempered. As shown in the drawings the reference numeral 22 indicates a steel bit having a pair of oppositely disposed longitudinally directed grooves or water courses 23 formed therein, with said water courses terminating in the drilling end or nose 24 of the bit. The nose end of the bit is flared outwardly to a diameter greater than the diameter of the bit proper with the water courses forming a web 25. The bit is projected into the forge through the entrance opening 14 a distance sufficient to position the enlarged nose or drilling end of the bit in substantially the middle of the main fire chamber 12 and directly opposite the fire pocket 11, as illustrated in Figure 3. If desired, an upper guide similar to the guide member 21 may be provided secured to the upper front portion of the forge above the lower guide member 21.

It will be noted from the description that when the drilling end of a bit is positioned in the forge supported on the shelf 20 and the guide member 21 thereof that flames entering from the lower and upper fuel supply pipes 16 and 17, respectively, will follow the contour of the curved wall or the main fire chamber 12 and will consequently whirl around the nose portion of the bit without hitting directly on the steel. The nose portion of the bit is larger than the main portion of the bit and substantially thicker than the web 25. The fire pocket 11 assists the main chamber 12 to cause the nose to be heated prior to the heating up of the thin web portion 25, thereby causing an even heating of the different portions at the nose end of the tool obviating cracks and bursting of the metal at the drilling end of the tool. Bursting at the nose end of the tool occurs when a bit is heated in a manner to cause the thin web portion of the tool to be heated before the heavy sections of the tool are heated, resulting in the expansion of the thin portion of the tool prior to the expansion of the large sections of the tool, thereby causing the tool to crack and burst. These difficulties are overcome in the present invention, as hereinbefore stated. To get the best results a steel bit should be tempered at a rising heat and not at a falling heat. A bit to be tempered

should lay on the anvil after dressing until a hand can be laid on the same. The bit should then be put back into the forge and the nose end should be given a short heating 5 for a distance of about two inches on the tip of the bit until said nose portion reaches a dark cherry red color. The bit should now be removed and projected into a clean slack tub to cool the same without causing any 10 appreciable amount of heat to run down the body portion of the bit to expand the same, so that the steel at the nose end of the tool is not strained and consequently does not burst.

15 I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A bit forge comprising a framework, a metal casing mounted thereon, and a refractory lining in said casing consisting of 25 rings of different radial depths forming the interior of the forge into a main intermediate fire chamber, a rear fire pocket communicating with the main chamber, and a 30 front opening also communicating with the main chamber and permitting a tool to be tempered to be projected into the housing, with the nose of the tool positioned in substantially the middle portion of the main 35 chamber.

2. A bit forge comprising a framework, roller supports therefor to permit movement of the framework, a metal casing thereon open at one end and closed at the other end, 40 means on the framework for supporting a tool in position with one end of the tool projecting into the forge, and a refractory lining in said casing consisting of three concentric layers of fire brick forming an inner 45 lining section having a fire pocket therein, an intermediate lining section consisting of a single layer of fire bricks and forming a main fire chamber communicating with said fire pocket, and an outer lining section consisting of two concentric layers of fire brick 50 and forming an entrance opening through which the tool is projected into the forge permitting the nose of said tool to be positioned substantially in the middle portion 55 of said main fire chamber.

3. A bit forge comprising a framework, roller supports therefor, a metal casing supported on the framework with said casing open at one end and closed at the other, a 60 refractory lining in said casing with said lining comprising sections of different radial depths to form a large fire chamber within the central portion of the forge communicating with a rear fire pocket and a 65 front entrance opening with the diameter of

the entrance opening being greater than the diameter of the rear fire pocket and less than the diameter of said main fire chamber, a guide bracket mounted on the framework adapted to support a bit with the nose 70 end of said bit projecting through said entrance opening into the main fire chamber, and means for directing a plurality of flames tangentially into the main fire chamber to whirl around the nose of the tool 75 without directly hitting the same.

4. A bit forge comprising a framework, a metal casing mounted thereon, a refractory lining for said metal casing with different sections of the lining being of different radial depths to form a large intermediate fire chamber, a front opening of less diameter than the diameter of the main fire chamber, and a rear fire pocket communicating with the main fire chamber and of a 80 diameter less than the diameter of the front opening, and fuel supply pipes projecting into the lower and upper portions of the casing and through the middle section of the lining to direct flames tangentially into the 85 main fire chamber.

5. A bit forge comprising a metal casing open at one end and closed at the other end, a support therefor, a tool guide and support mounted on said portable support to hold a 90 tool in position with one end thereof projecting into the forge, a lining in said casing comprising an intermediate section, a front section of a depth greater than the intermediate section, and a rear section of a 95 depth greater than the front section, said sections forming the interior of the forge into a large intermediate fire chamber, a rear fire pocket communicating therewith, and a front opening communicating with said fire chamber and open at the open end of said casing, and fuel supply pipes projecting through the casing and through the intermediate lining section into the main 100 fire chamber to direct flames around the end 105 of the tool to be tempered.

6. A bit forge comprising a metal casing open at one end and closed at the other end, a refractory lining in said casing comprising an intermediate section of a selected 110 depth, a front section of a depth greater than the depth of the intermediate section, and a rear section of a depth greater than the front section, said lining sections forming the interior of the forge into a large 115 main fire chamber in the intermediate section, a rear fire pocket in the rear section, and an entrance opening in the front section.

7. A bit forge comprising a casing open 120 at one end and closed at the other end, a refractory lining in said casing comprising an intermediate section, a front section of greater depth, and a rear section of a depth greater than the depth of the front section, 125 130

- thereby forming the interior of the forge into a main fire chamber, a rear fire pocket communicating therewith, and a front opening communicating with the main fire 5 chamber and open at the open end of the casing to permit a tool to be tempered to be projected into the main fire chamber adjacent said rear fire pocket, and means for directing flames into the main fire chamber.
10. 8. The combination with a bit forge, of a lining therefor comprising a rear section constructed of a plurality of annular concentric rows of refractory fire bricks, a front section constructed of a plurality of 15 annular concentric rows of fire bricks of a depth less than said rear section, and an intermediate section positioned between the rear section and said front section and of a depth less than the depth of either of said 20 sections, said sections dividing the interior of the forge into a fire chamber positioned between and communicating with a rear fire pocket and a front entrance opening.
9. A bit forge comprising a metal casing 25 open at the front end and having the other end closed by a rear wall having a central opening therein, overlapping plates secured to said rear wall to close the opening thereof, a support for said casing, a lining in said 30 casing constructed of a plurality of annular rows of fire brick arranged to divide the interior of the forge into a rear fire pocket, a fire chamber communicating therewith, and an entrance opening communicating with 35 said fire chamber, and means for directing flames tangentially into the fire chamber.
10. In combination in a forge, a casing having an annular chamber, parallel flame inlets positioned to discharge tangentially 40 into said chamber, said inlets being diametrically opposite each other and arranged to augment and continue the flame discharged from each other in order to maintain a substantially continuous and whirling ring of 45 flame within said chamber, and means in said casing for defining an opening to receive the end of a tool to be treated, said opening being disposed in communication with the center of said chamber so that said 50 end of the tool can be positioned within the center of said ring of flame in said chamber.
11. In combination in a forge, a casing having an annular chamber disposed in a vertical plane, upper and lower tangential 55 parallel flame inlets disposed in communication with said chamber, said inlets being arranged to augment and continue the flame discharged from each other in order to maintain a substantially continuous and whirling ring of flame within said chamber, said casing 60 having an opening disposed in communication with the center of the ring of flame for receiving the end of a metal piece to be treated whereby the ring of flame encircles said end of the piece and heats the portions 65 of the same uniformly, and means in said casing for defining a fire pocket disposed in alignment with said opening and arranged to assist the flame chamber in causing the extreme end or nose of said metal piece being treated to be heated prior to other portions thereof and to thus insure an even heating of the different portions of said end of the metal piece. 70
12. In combination in a forge, a casing having an annular flame chamber disposed in a vertical plane, a pair of parallel flame inlets discharging tangentially and in opposite directions into said chamber, said inlets being diametrically opposite each other and arranged to augment and continue the flame discharged from each other after the flame from each has traveled approximately 180° in said chamber in order to maintain a substantially continuous ring of flame within 75 the chamber, and means in said casing for defining a fire pocket disposed in alignment with said opening and arranged to assist the flame chamber in causing the extreme end or nose of a metal piece being treated to be heated prior to other portions thereof and to thus insure an even heating of the different portions of said end of the metal piece. 80
13. In combination in a forge, a casing having a substantially annular chamber therein, spaced flame inlets positioned to discharge tangentially into said chamber, said inlets being arranged to augment and continue the flame discharged from each other in order to maintain a substantially continuous and whirling ring of flame within said chamber, means in said casing for defining an opening to receive the end of the tool to be treated, said opening being disposed in communication with the center of said chamber so that said end of the tool can be positioned within the center of said ring of flame in said chamber, and means in said casing for defining a fire pocket disposed in alignment with said opening and arranged to assist the flame chamber in causing the extreme end or nose of a metal piece being treated to be heated prior to other portions thereof and to thus insure an even heating of the different portions of the said end of the metal piece. 90
